UNITED STATES PATENT OFFICE

2,450,993

ELECTRIC MOTOR-DRIVEN CONCRETE
MIXER

Joseph Santagata, Cranston, R. I.

Application April 5, 1945, Serial No. 586,690

3 Claims. (Cl. 259—177)

1

This invention relates to so-called portable concrete mixers, and the purpose thereof is to substitute electric motor-driven means for the customary employed gasoline engine, whereby to simplify the overall structure and to achieve other and desirable ends.

Manifestly, the average person, that is, the ordinary user, is not especially equipped with knowledge in reference to gasoline engines, such as are used on these mixing machines. Therefore, by substituting an electric motor included in the drive, anyone, without special knowledge or machinery, can buy or rent a mixer, simply plug in any house current, and then carry on the desired aims successfully. As such, the machine is not only advantageous to the general public, but is especially useful to farmers.

In addition to the above, a concrete mixer provided with an electric motor propulsion unit or means is advantageous in reference to maintenance or repair work, as the parts of the electric drive can be replaced and repaired with greater expediency and reliability than would be susceptible of accomplishment if an intricate gasoline engine were to be contended with.

A concrete mixer constructed in accordance with the principles of this invention can be used profitably by contractors due to low operating costs. Being a silent drive, the machine can be operated day or night. On the contrary, gas-driven machines can be operated only during periods, generally in the daytime, when noisy operation is permissible. What is more important, a machine including an electric drive, there being no fumes or consumption of fuel, can be operated inside of a building if necessary, and, too, this machine can mix more concrete than the gasoline type, this with less horse-power and at more than half the cost. And finally, because of this type of drive, the machine can be built with the requisite compactness and a reduction in weight and towed from place to place with the least amount of time and effort.

Other features and advantages will become more readily apparent from the following description and the accompanying illustrative drawings:

In the drawings, wherein like numerals are employed to designate like parts throughout the same—

Figure 1 is an end elevational view of a more or less conventional portable type concrete mixer equipped with an electric motor-driven structure constructed in accordance with the principles of the invention.

2

Figure 2 is an end elevation, the gear housing or cover being removed, and the view being taken somewhat on the plane of the line 2—2 of Figure 1, looking in the direction of the arrows.

Figure 3 is a view looking in the opposite direction, this on the plane of the line 3—3 of Figure 1.

Figure 4 is an "exploded" view, that is, a view showing the individual parts which go to make up the sprocket wheel and pinion assembly.

10 Figure 5 is a similar view with the parts of said assembly arranged and joined together in operative relationship.

15 Referring to the drawings by distinguishing reference numerals, it will be seen that the usual type of concrete containing and mixing receptacle is denoted, this at 6. It is mounted for rotation in bearings 7 on the frame structure 8 supported from the chassis 9, the latter carried by customary ground-engaging wheels 10. The customary crank means is provided at 11 for dumping the mixer 6.

20 I call attention at this time to the pinion and sprocket assembly means shown in Figures 4 and 5. Here we see an adapter bracket or fixture 12 bolted to a frame member 13, said fixture being provided with an axle 14 to accommodate the driven rotor unit. This comprises a bearing sleeve 15 containing a "Timken" bearing 16 and having outstanding lugs 17, the latter being bolted to the marginal portion of the pinion gear 18. Parts 15 and 18, of course, surround the shaft 14. There is a similar and longer sleeve at 19 surrounding the shaft, and this is provided with outstanding circumferentially spaced lugs 20 secured by the same bolts to the opposite face or side of the gear 18. The right-hand end portion of the sleeve forms a hub extension 21 for the sprocket wheel 22, the latter being fitted on the hub and bolted to the driving lug 23. The aforementioned shaft extends through the bearing unit 24, where it is secured properly in place by nuts, or the like, 25 (see Figure 5).

25 The sprocket wheel 22 is driven by a sprocket chain 26 (see Figure 2), which sprocket chain is connected with a smaller sprocket wheel 27 on the shaft of the electric motor 28, the latter suitably mounted on the chassis. The large power takeoff gear is indicated at 29, this being connected to the right-hand end of the rotating shaft of the mixing drum 6.

30 In actual practice, the gears and sprocket wheels and chain and associated parts are enclosed in an appropriate gear casing or housing 55 indicated generally by dotted line 30 in Figure 1.

This is of any appropriate construction, and is therefore not detailed.

It is thought that persons skilled in the art to which the invention relates will be able to obtain a clear understanding of the invention after considering the description in connection with the drawings. Therefore, a more lengthy description is regarded as unnecessary.

Minor changes in the shape, size and arrangement of details coming within the field of invention claimed may be resorted to in actual practice, if desired.

I claim:

1. A special motion take-off and transmitting gearing assembly for use on a conventional concrete mixer machine for coaction with a standard-type driving gear on the mixer drum and adapted to accommodate a standard sprocket gear equipped electric motor comprising an adapter fixture adapted to be secured rigidly to the frame of the mixer machine, and including an outstanding axle, and a rotor including hub means mounted for rotation on said axle, said hub means including a motion transmitting gear located for coaction with the driving gear on said mixer drum, and further including a sprocket wheel arranged for coaction with a supplemental sprocket driven by said motor.

2. In a gear and sprocket adapter assembly for use on a concrete mixer equipped with an electric motor, a bracket adapted to be rigidly mounted on a part of the mixer frame, said bracket having an outstanding axle, a sleeve mounted on the inner end portion of said axle and abutting the bracket, said sleeve having outstanding lugs, a gear fastened to said lugs and surrounding the axle, a second somewhat longer sleeve mounted for rotation on said axle and having lugs connected to the opposite side of said gear, said second sleeve having outstanding lugs and a portion

projecting well beyond said lugs and constituting a hub, a sprocket wheel mounted on said hub and secured to said outstanding lugs, and means for assembling and maintaining all parts on said axle.

3. In a silent electric drive for a concrete mixer machine which is characterized by a wheel supported chassis and frame, said frame being adapted to suspend a concrete mixer drum and being provided with usual bearings, said drum being provided with shaft means mounted for operation in said bearings, the shaft means at one end being provided with a driven gear, an adapter bracket secured to said frame and including an outstanding axle, gearing means embodying a hub mounted for rotation on said axle, said hub embodying a motion transmitting gear aligned with and serving to rotate said driven gear, said hub further including a sprocket wheel, an electric motor mounted on the chassis and including a drive shaft and sprocket wheel on said drive shaft, said sprocket wheel being lined up with the first named sprocket wheel, and a sprocket chain trained over said sprocket wheels.

JOSEPH SANTAGATA.
